METHOD OF MAKING WELL PIPE

Ashton Reed, Bakersfield, Calif.

Application April 14, 1939, Serial No. 267,839

3 Claims. (Cl. 29—157)

This invention relates to well drilling equipment and relates more particularly to pipe or tubing for use in wells and to methods of making the same. A general object of this invention is to provide a strong, long-wearing well pipe and improved methods of constructing such pipe.

Oil wells and gas wells are being drilled to very great depths making it necessary to employ heavier and stronger drilling equipment. For example, in the rotary method of drilling the drill pipe, to which the drilling tool is attached, has been strengthened by upsetting the threaded end portions of the pipe sections to provide increased wall thickness at these points. The upset joints of this type of drill pipe have a very high efficiency of strength and dependably withstand the stresses to which they are subjected. There are two general types of upset drill pipe, namely, the internal upset pipe and the external upset pipe. The internal upset pipe has its fluid passage restricted at each joint and these restrictions interfere with the fluid flow and prevent the operation of certain tools in the drilling string. For this reason the external upset drill pipe is superior to the internal upset pipe and has gone into extensive use. It has been found, however, that the upset portions of the drill pipe wear extensively through their engagement with the wall of the well during the rotary drilling operation, and when the pipe is moved into and out of the well. An external upset portion of the pipe usually wears unevenly and soon becomes out of round. This condition sometimes causes failure through unbalanced stresses at the joint. Attempts have been made to correct this condition by heat treating the upset pipe portions and by welding on hard materials at the joints. These attempts have not proven altogether successful as the methods employed to harden the upset portions change the character and structure of the original metal of the pipe, setting up strains and causing flaws to develop.

Another object of this invention is to provide externally upset well pipe such as drill pipe or well tubing that is effectively protected against wear at the upset enlargements.

Another object of this invention is to provide externally upset well pipe embodying hard abrasion resisting and wear resisting sheaths dependably bonded directly to the metal of the upset pipe portions to fully protect the same against wear.

Another object of this invention is to provide

well pipe of the character mentioned in which the wear resisting sheaths may be integral parts of uniform texture and character to offer uniform resistance to wear throughout the circumference of the upset portions.

Another object of this invention is to provide well pipe of the character mentioned in which the wear resisting sleeves and sheaths are applied in such a manner that they do not disturb, injure, or weaken the granular structure or molecular structure of the metal of the pipe.

Another object of this invention is to provide externally upset well pipe of the character referred to that is simple and inexpensive and that is strong and durable.

Another object of this invention is to provide a method for manufacturing upset well pipe in which hard wear-resisting sheaths are provided on the upset pipe portions at the time of their formation.

Another object of this invention is to provide a method for making upset well pipe in which the metal of the pipe body is bonded, welded, or fixed to the wear resisting tubular sheaths when the pipe is upset and when its metal is in a heated, substantially plastic state.

Another object of this invention is to provide a method of the character mentioned in which the forces employed to form or upset the pipe bring the metal of the pipe in intimate bonding contact with the metal or material of the protective sheaths.

A further object of this invention is to provide a method of the character mentioned that is simple and readily carried out, and that may be performed without delaying or interfering with the upsetting operations.

The various objects and features of my invention will be fully understood from the following detailed description of typical preferred forms of apparatus and manners of carrying out the method of the invention, throughout which description reference is made to the accompanying drawing, in which:

Fig. 1 is a side elevation of a length or section of well pipe of the present invention with an end portion broken away to appear in longitudinal cross section. Figs. 2 and 3 are diagrammatic views illustrating the successive steps in one manner of carrying out the method of the invention, and Figs. 4 and 5 are similar diagrammatic views illustrating successive steps in another manner of performing the method.

In Fig. 1 of the drawing I have illustrated a

length of pipe that may be considered drill pipe of the character employed in the rotary method of well drilling, that is, the length of pipe illustrated may be taken as a section of a rotary well drilling string. It is to be understood that the pipe may have other uses in a well. For example, it may be employed as a section of a string of well tubing, or the like. I will proceed with a detailed description of the typical length 10 of pipe of the invention illustrated in Fig. 1 and will follow such description with a disclosure of the methods of the invention.

The well pipe or drill pipe of the invention may be said to comprise a pipe body 10, upset 15 end portions 11 on the body 10, and wear resisting sleeves or sheaths 12 on the upset portions 11.

The body 10 of the pipe may be of typical construction and design, that is, it may be a simple, 20 elongate tubular element. The pipe may be of seamless construction, that is, it may be formed by piercing a solid billet or it may be of lap weld or butt weld construction. The fluid passage 13 extends longitudinally through the pipe 25 section from one end to the other and is preferably of uniform diameter. The pipe body 10 is preferably formed of steel, for example, it may be formed of Bessemer steel or open hearth process steel.

30 The upset end portions 11 are provided on the body 10 to give the pipe body increased strength and wall thickness at its points of connection with the other elements of the well string or drilling string and to strengthen the pipe assembly adjacent these points. The pipe section 35 of the invention may have an upset portion 11 at one end only, or may have upset portions 11 at its opposite ends, as illustrated. The upset portions 11 are, of course, integral parts of the 40 pipe body 10 and are formed of the same material or steel as the body.

The portions 11 are in the nature of cylindrical external enlargements of the pipe body 10. Where the pipe body 10 has two upset portions 45 11 they may be of the same diameter and of substantially the same length. The inner ends 14 of the upset portions 11 are beveled or tapered to merge with the external surface of the pipe body 10. The end portions or the upset portions 50 11 of the pipe section are provided with threads for mating with threads of the other parts of the well string. Either one or both of the upset end portions 11 may be provided with an external thread or either one or both of the portions 11 55 may be provided with an internal thread, as conditions may require. In the case illustrated one upset portion 11 has an internal thread 15 and the other end portion 11 carries an external thread 16. The first mentioned upset portion 11 60 has a tapered socket whose wall carries the internal thread 15 while the other upset portion 11 is provided with a longitudinally projecting pin 17 which carries the external thread 16. The present invention is not primarily concerned 65 with the construction, arrangement or formation of the connecting threads 15 and 16.

The protective sleeves or sheaths 12 are important features of the invention. The sheaths 12 are provided to protect the upset pipe portions 70 11 against wear through contact with the wall of the well when the well string is rotated during the drilling operations and when the pipe is run into and out of the well. In the preferred construction the sheaths 12 protect or surround 75 substantially the entire surface parts of the upset

portions 11. The sheaths 12 are preferably integral continuous tubular elements and it is preferred to provide a single tubular sheath on each upset pipe portion 11. The sheaths 12 may be formed of any suitable or selected abrasion resisting and wear resisting material, for example, they may be formed of materials alloyed or compounded for this use. The tubular protective sheaths 12 may extend from adjacent the outer ends of the upset portions 11 to the reduced body 10 of the pipe section. There may be exposed or uncovered surfaces 18 of short length at the outer extremities of the upset portions 11.

It is a feature of the invention that the sheaths 12 are permanently bonded with the metal of the 15 upset portions 11. The sheaths 12 are incorporated in the pipe sections at the time of formation of the upset portions 11 and the plastic heated metal of the pipe is expanded against and intimately bonded with the metal of the 20 sheaths 12. The internal surfaces of the sheaths 12 may be roughened, knurled or grooved to assure a better bond between the sheaths and the metal of the pipe or the sheaths 12 may have pluralities of perforations 19 into which the 25 metal of the portions 11 is pressed or made to flow to provide positive interlocking connections with the sheaths 12. The sheaths 12 are applied to or embodied in the upset portions 11 without changing the granular structure or the 30 character of the pipe metal and without resorting to acetylene welding or electric welding which subjects the metal to excessive temperatures and without resorting to heat treatment processes which change the character of the 35 metal. The wall thickness of the protective sheaths 12 may be varied as conditions may require. Where the sheaths 12 are formed of hard, long wearing material the sheaths may have thin walls to reduce the wall thickness of 40 the upset portions 11 to a minimum degree. The sheaths 12 are embedded in the upset portions 11 and may have smooth cylindrical external surfaces so that they do not present edges, shoulders, or other projections on the pipe.

It is believed that the utility and the features 45 of the well pipe of the invention will be readily apparent from the foregoing detailed description. The sheaths 12 fully and effectively protect the upset pipe portions 11 against wear through contact with the wall of the well and through contact with the well casing and other objects. The sheaths 12 may cover the tapered end parts 50 14 and may extend to or adjacent the outer extremities of the portions 11 and thus offer 55 complete protection for the upset portions. As above described, the sheaths 12 may be continuous and tubular and of uniform construction, to offer uniform protection for the upset portions 11. Thus the sheaths 12 prevent uneven wearing 60 of the upset pipe portions and eliminate the possibility of failure due to unbalanced stresses. The sheaths 12 are directly bonded with the metal of the pipe portions 11 and are locked to the portions 11 in such a manner that they cannot work 65 loose or become detached and constitute permanent parts of the pipe structure. The sheaths 12 are applied in such a manner that the character and structure of the metal comprising the pipe portions 11 are unchanged and no stresses 70 or flaws are produced.

The method of the invention carried out in the manner illustrated in Figs. 2 and 3 of the drawing, may be said to comprise the arrangement of a pre-heated sheath 12 in a forming 75

bowl or die D, the arrangement of the end portion of a pipe body 10 in the die D when heated to plasticity or to a temperature suitable for upsetting and the upsetting of the heated end portion of the pipe body to effect expansion of the sheath 12 and shaping of the pipe portion 11 and the sheath 12 into conformance to the die D.

In the method shown in Figs. 2 and 3 the sheath 12 is pre-formed to be of approximately its final length, but to be smaller in diameter than the opening or socket S of the die D. In practice the sheath 12 as initially formed may be of just sufficient diameter to receive or surround the pipe body 10 with slight clearance. As illustrated the sheath 12 may be provided with the above described perforations 19. The pre-formed sheath 12 is heated prior to or following its introduction to the die D and its temperature is such that it may be expanded to its final size without fracture or strain. The temperature to which the sheath 12 is heated of course depends upon the character of the metal of which it is formed. The pre-formed and pre-heated sheath 12 is positioned in the socket S to have its inner end engage against the tapered inner or bottom wall of the socket.

The pipe body 10 may be introduced into the die D before, simultaneously with, or following the arrangement of the sheath 12 in the die. The pipe body 10 is located and held to have its upset portion 11 of the required length when the upsetting operation is completed. The pipe body 10 or at least the end portion of the body 10 is heated to be readily formed or upset. In other words, the end portion of the pipe body 10 is heated to be substantially plastic and capable of easy deformation.

The upsetting of the pipe may be performed by a suitable mandrel M introduced into the end portion of the pipe located in the die D as described above. The mandrel M is proportioned to give the pipe its desired internal diameter and has an inwardly facing annular shoulder 20 engageable against the end of the heated pipe P. The outer portion 21 of the mandrel M is proportioned to slidably operate in the socket S and when the mandrel M is moved inwardly relative to the die D the heated substantially plastic end part of the pipe body is upset to conform to the wall of the socket S in the manner well known to those skilled in the art. The heated compressed metal of the pipe flows or spreads outwardly to expand the preheated sheath 12 and to bond, fuse or weld with the metal of the sheath. The metal of the pipe flows into and occupies the perforations 19 to lock the sheaths 12 to the upset portion 11. The sheath 12 is expanded and shaped into conformance to the wall of the socket S and the pipe portion 11 is given its shape by the upsetting operation.

It will be observed that the upsetting of the end portion 11 of the pipe results in the direct embedding of the wear resisting sheath 12 in the peripheral part of the upset pipe portion 11. The application of the sheath 12 to the upset portion 11 is accomplished during the formation of the portion 11 and does not necessitate subsequent heating or working of the metal which might result in a change in its texture and the development of stresses, etc. Following the above described operations the pipe may be machined and the threads cut in the usual manner.

The method of the invention illustrated in Figs. 4 and 5 of the drawing may be said to

comprise, generally, the arrangement of a pre-heated and pre-shaped sheath 12 in the die D, the arrangement of the heated pipe body 10 in the die D, and the upsetting of the heated pipe to bond with the sheath 12 and to assume the required shape.

In carrying out the method illustrated in Figs. 4 and 5 of the drawing the sheath 12 may be pre-formed to its final shape and to rather accurately fit the socket S of the die D. In this case the sheath 12 has a tapered end portion 23 adapted to seat against the tapered bottom wall of the socket S. In addition to the perforations 19 described above the sheath 12 may have internal grooves, ribs or knurling 24 to 15 assure the dependable, permanent bonding of the pipe metal with the sheath. The sheath 12 is preferably heated prior to the upsetting operation or prior to its introduction to the die socket S.

The pipe section or body 10 is introduced to the die D to extend through the sheath 12 and to have its end in the required position for the upsetting operation. The pipe is, of course, held or fixed in this position. The pipe body, or at least the end portion to be worked upon, is heated to the required temperature for the upsetting operation and this is preferably done before the pipe is introduced to the die D. The upsetting of the pipe may be performed by the mandrel M, as described above, to provide the pipe with its upset end portion 11. The metal of the upset end portion 11 is forced outwardly into firm positive contact with the roughened or knurled interior of the sheath 12 and the compression of the metal against the sheath assures the proper shaping of the sheath to the wall of the die socket S. In this manner of performing the method there is no danger of excessively stressing or straining the sheath 12 and the sheath may be constructed of a hard material unsuited for use in the previously described method. Following the upsetting operation the pipe is removed from the die D and is machined to have the threads, etc.

It is to be particularly noted that the method of the invention carried out in the manners described above, provides for the application of the protective sheaths 12 to the upset portions 11 without in any way changing the character of the metal of the pipe or the character of the metal of the sheaths. The pipe metal being upset outwardly against the internal surfaces of the sheaths 12 permanently bonds with the sheaths and the sheaths are, in effect, embedded in the original metal of the pipe.

Having described only typical preferred forms and applications of my invention and manners of carrying out the method, I do not wish to be limited or restricted to the specific details herein set forth, but wish to reserve to myself any variations or modifications that may appear to those skilled in the art or fall within the scope of the following claims:

Having described my invention, I claim:

1. The method of applying a tubular wear resistant sheath to a well pipe comprising forming the sheath to have an internal diameter greater than the initial external diameter of the pipe and to have a roughened internal surface, heating the sheath, placing the heated sheath in a die which conforms to the exterior of the sheath, heating an end portion of the pipe to plasticize the same, inserting said heated end portion of the pipe in the die to be within the heated sheath, subjecting said

heated end portion of the pipe to longitudinally directed compression forces to upset said portion so that it engages in, conforms to and bonds with the interior of the sheath, and then removing the 5 pipe with the sheath thereon from the die.

2. The method of applying a wear resistant sheath to a well pipe comprising forming a wear resistant sheath with a perforated portion having an internal diameter materially greater than the 10 initial external diameter of the pipe, heating the sheath, inserting the sheath in a die shaped to conform to the exterior of the sheath, heating an end portion of the pipe to render the same plastic, inserting the heated end portion of the 15 pipe into said die to be received in the heated sheath, increasing the wall thickness of said end portion of the pipe to cause the metal thereof to flow into the perforations of the sheath and to conform to and bond with the internal surface 20 of the sheath by externally upsetting said end portion of the pipe while within the sheath and

die, and then removing the pipe with the sheath thereon from the die.

3. In the manufacture and forming of a length of drill pipe, forming a wear taking sheath having a portion with a rough internal surface and 5 an internal diameter materially greater than the external diameter of the pipe, heating the sheath, placing the heated sheath in a die which substantially conforms to the exterior of the sheath, heating an end portion of the pipe to render it 10 plastic or readily formable, inserting the heated end portion of the pipe in the die to assume a position within the heated sheath, upsetting said heated end portion of the pipe by subjecting it to longitudinal compression forces to cause the 15 said portion of the pipe to conform to and securely bond with the rough internal surface of the sheath, and then removing the pipe with the sheath thereon from the die.
